By: *Fred J. Hanson*
ATTORNEY.

UNITED STATES PATENT OFFICE.

HERMAN J. EBERLE, OF ST. LOUIS, MISSOURI.

REMOVABLE FLOOR-FORM SECTION FOR USE IN CONNECTION WITH COLUMN-FORMS USED IN SLAB CONSTRUCTION.

1,379,003.

Specification of Letters Patent.

Patented May 24, 1921.

Application filed August 4, 1919. Serial No. 315,225.

To all whom it may concern:

Be it known that I, HERMAN J. EBERLE, a citizen of the United States, residing in the city of St. Louis and State of Missouri, ⁵ have invented certain new and useful Removable Floor-Form Sections for Use in Connection with Column-Forms Used in Slab Construction.

My invention relates to removable floor ¹⁰ form sections for use in connection with column forms used in slab construction, and has for its object to provide a removable and separable form adapted to be supported by the floor-joist at an elevation to provide ¹⁵ the slab construction with a flat lower or ceiling surface, or with a depressed ceiling surface, as desired.

A further object of the invention is to provide a two piece form section to permit ²⁰ the same to be positioned in sections, also removed in sections.

A still further object of the invention is to provide a form that will be simple in construction, durable, easy to place into position, and to remove, and one which will materially reduce the cost of slab construction, as no sawing of the wooden floor form around the head of the column forms is necessary, which sawing of material results ²⁵ in the waste of floor form lumber.

A further object of the invention is to provide a floor form section which can be re-used.

With the above and other objects in view, ³⁵ the invention consists in the novel construction, arrangement and combination of parts hereinafter described and finally pointed out in the claims hereto appended.

Referring to the accompanying drawings ⁴⁰ forming a part of this specification wherein like characters denote similar parts throughout the several views:

Figure 1, is a plan view of my improved removable and separable form positioned ⁴⁵ adjacent the head of a column form and supported by the floor joist.

Fig. 2, is a sectional elevation showing my improved form section in a position in aline with the floor form so as to form a ⁵⁰ ceiling effect.

Fig. 3, is a sectional elevation similar to Fig. 2, showing my improved form arranged at a position below the floor form proper to provide a depressed ceiling portion at the ⁵⁵ head of each supporting column.

Fig. 4, is a detail of a flat slab floor construction showing a flat ceiling.

Fig. 5, is a detail of a flat slab floor construction showing a depressed ceiling portion at the head of the supporting column. ⁶⁰

Fig. 6, is a plan view of the separable form sections assembled with a portion of the plates thereof broken away.

Referring to the drawings, the reference character 1 designates the usual floor joist ⁶⁵ while 2 designates the sheathing of the floor form.

The reference character 3 designates a suitable column form having the funnel shaped cap 4 which is provided at its upper ⁷⁰ edge with the shoulder or flange 5.

The floor form is provided with a removable form receiving opening 6.

In carrying out the aim of my present invention, I employ a removable and separable form comprising two sections A and B. Each form section A and B comprises the long frame members 7, and the short frame members 8, which frame members are reinforced or strengthened at their corners ⁷⁵ by means of suitable brace members 9. Each frame section A and B of the form is provided with a suitable top plate 10 having a semi-circular opening or cutaway portion 11 to provide a circular opening to receive ⁸⁰ the cap 4 of the column form 3 when the removable form is assembled in position within the opening 6 of the floor form.

The flange or shoulder 5 of the cap of the column form 3, is adapted to rest ⁸⁵ upon the upper face of the cover plate 10 of the removable form, as clearly shown in Figs. 2 and 3. The two sections of the removable form frame are held in the desired position with relation to the floor ⁹⁰

form proper by means of suitable supporting members 12. The removable form frame, when assembled, is adapted to rest upon the supporting member 12, as clearly shown in Figs. 2 and 3. The form supporting members 12 may be united at their corners to form a frame, if desired. The supporting members 12 are nailed as at 13, or otherwise securely fastened to the joists ⁹⁵

1 to hold and support the removable form ¹⁰⁰ at the desired elevation within the opening 6.

When the flat slab construction designated C, is to have a flat ceiling effect adjacent the head 14, of the column 15, as shown ¹⁰⁵

110

in Fig. 4, the removable form is positioned within the opening 6 so that the top face of the plate 10, thereof, will lie in a plane with the top face of the floor form, as 5 clearly shown in Fig. 2.

Whenever the flat slab construction C, is to be provided with a depressed ceiling portion D at the head 14 of the supporting column 15, the removable form is so arranged within the opening 6 that the upper face of the top plate 10 will lie at a suitable elevation below the top face of the floor frame, as clearly shown in Fig. 3.

It will be here observed that the height 15 of the depression D in the ceiling at the head of a supporting column may be varied, as desired, by adjusting the removable form frame to the desired position within the opening 6 of the floor form.

20 It is possible with my improved removable form to remove the column form 3 from the concrete column 15 much sooner than where the floor form adjacent the head of a column form is not provided with a removable form section.

To remove my improved removable form section from the opening 6 of the floor form after the flat slab structure C and supporting columns 14 have sufficiently set, I 30 remove the supporting members 12 from the joists and each form section A and B is then easily lowered and removed from the opening 6, as is manifest. After this has been done, the removable column form is 35 then removed from around the concrete column 15 and head portion 14 thereof.

From the foregoing description, it will be evident that I have provided a removable and separable form section which can 40 be quickly assembled within a floor form opening 6 surrounding the head 4 of a column form 3, and quickly removed after the slab and column structure have been formed. It is also evident that the form 45 section can be re-used after being removed from the floor form opening 6.

The many advantages of the herein described removable form will readily suggest themselves to those skilled in the art to 50 which it appertains.

I do not wish to be understood as having limited myself to the exact details of construction shown and described, but desire to have it understood that the removable 55 form I have shown in the drawings is merely illustrative, as it is manifest that various minor changes may be made in the form, shape and particular arrangement of parts without departing from the spirit of 60 my invention, hence reserve the right to

make any such changes or modifications as may fairly fall within the scope of the appended claims when fairly construed.

What I claim is:

1. In combination with a floor form having an opening and the head of a column form, a removable form comprising two units positioned in the floor form opening to close the opening between the side walls of the floor form opening and the head of the column form, and means removably fixed to the floor joist for positioning the removable form section at any desired elevation within the floor form opening. 65

2. In combination with a floor form having an opening and the head of a column form, a separable two piece form section positioned in the floor form opening having a central opening to receive the head of a column form, and a removable frame fixed to the floor joist for supporting the form section at any desired elevation in the floor form opening. 75

3. In combination with a floor form having an opening and the head of a column form, a separable two piece form section having a column head receiving opening positioned in the floor form opening, and a rectangular frame removably fixed to the floor joist for supporting the form section 80 in the floor form opening at an elevation to provide a depressed ceiling portion of the desired height. 85

4. In combination with a floor form for flat slab construction having an opening and the head of a column form, of a removable and separable form consisting of two sections having a column form head receiving opening positioned in the floor form opening and cleats removably fixed to the floor joist for supporting the form section at an elevation in the floor form opening to produce a flat ceiling effect, or a depressed ceiling effect, of a desired height, when the forms are filled with a cementitious material. 95

5. In combination with a floor form for slab construction and the upper end of a column form, of separable form units each consisting of a supporting frame and a top plate for each frame, said units being positioned in the floor form opening and encircling the upper end of a column form and cleats removably fixed to the floor joist for supporting the separable form units at any desired elevation in the floor form opening. 100

In testimony whereof I have hereunto signed my name to the specification. 115

HERMAN J. EBERLE.
